(57) **CLAIM**

The ornamental design for a landscape edging stake, as shown and described.

DESCRIPTION

FIG. 1 is a perspective view of a landscape edging stake showing my new design;

FIG. 2 is a bottom perspective view thereof;

FIG. 3 is a left-side elevational view thereof;

FIG. 4 is a front elevational view thereof, rear being a mirror image thereof;

FIG. 5 is a right-side elevational view thereof;

FIG. 6 is a top plan view thereof; and,

FIG. 7 is a bottom plan view thereof.

The broken lines represent portions of the stake and form no part of the claimed design.
